UNITED STATES PATENT OFFICE.

GEORGE KOPP, OF CLEVELAND, OHIO.

DESIGN FOR A PASTRY-CABINET FRAME.

SPECIFICATION forming part of Design No. 30,798, dated May 16, 1899.

Application filed March 13, 1899. Serial No. 708,964. Term of patent 3½ years.

To all whom it may concern:

Be it known that I, GEORGE KOPP, a citizen of the United States, residing at Cleveland, Cuyahoga county, State of Ohio, have invented and produced a new and original Design 5 for Pastry-Cabinet Frames, of which the following is a specification, reference being had to the drawing forming a part thereof.

In the drawing the figure represents a view 10 in perspective of my cabinet-frame.

As shown in said drawing, the leading features of my design consist in the shape of the cabinet and in the arrangement and configuration of the partitions and panels.

The cabinet is of substantially inverted-U 15 shape in section and is divided into four compartments A B C D by means of the horizontal partition E and the vertical partition F, that cross each other at right angles. The 20 upper compartment A is equally divided by means of the vertical partition G. The front of the cabinet is provided with oblong panels H H, that extend centrally across the same. The edges of the panels and the edges of the 25 cabinet below the panels are protected by op-

positely-inclined strips, giving the appearance of a V-shaped reinforcement J to said edges. The vertical partitions and the edges of the cabinet above the panels and the lower half of the central vertical partition are each 30 faced with a flat strip K, provided with beads k along its edges. The V-shaped ridge L is formed along the center of the top of the cabinet, extending lengthwise thereof. The rear and ends of the cabinet are plane surfaces 35 without any ornamentation.

The cabinet is supported by the base-pieces O, that are secured to the bottom at the four corners.

I claim—

The design for a pastry-cabinet frame herein shown and described.

In witness whereof I sign this application, in the presence of two witnesses, this 9th day of March, 1899.

GEORGE KOPP.
